CLAIM

The ornamental design for a drawer for refrigerator, as shown and described.

DESCRIPTION

1. Drawer for refrigerator
- 1.1 : Perspective
- 1.2 : Front
- 1.3 : Back
- 1.4 : Left, the right view being a mirror image
- 1.5 : Top
- 1.6 : Bottom

(Continued)

The broken lines depict portions of the drawer for refrigerator that form no part of the claimed design. This design is for a drawer for refrigerator with a recessed handle at the top front part.
